CLAIM

The ornamental design for a drop foot brace as shown and described.

DESCRIPTION

FIG. 1 is a perspective view of drop foot brace showing my new design;

FIG. 2 is another perspective view thereof;

FIG. 3 is another perspective view thereof;

FIG. 4 is a front elevational view thereof;

FIG. 5 is a right side elevational view thereof;

FIG. 6 is a left side elevational view thereof;

FIG. 7 is a a is a top plan view thereof;

FIG. 8 is a a is a bottom plan view thereof.

FIG. 9 is a perspective view of the drop foot brace of FIG.

1, shown with the loop closed for clarity of disclosure;

FIG. 10 is an enlarged view of portion 10 shown in FIG. 5;

and,

FIG. 11 is an enlarged view of portion 11 shown in FIG. 6. The broken lines in the drawings depict portions of the drop foot brace that form no part of the claimed design.

The dot-dash broken lines represent boundaries of the enlarged portions and form no part of the claimed design.

1 Claim, 11 Drawing Sheets
